[57] CLAIM

The ornamental design for a cabinet for housing stereo components, as shown and described.

DESCRIPTION

FIG. 1 is a back elevational view of a cabinet for housing stereo components embodying my new design;

FIG. 2 is a top plan view thereof;

FIG. 3 is a front elevational view thereof; and

FIG. 4 is a side elevational view thereof.
The side of the cabinet not shown is a mirror image of the side shown in FIG. 4.FIG. 1

FIG. 2

FIG. 3

FIG. 4
